(57) **CLAIM**

The ornamental design for a notebook computer, as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view showing an opened state thereof;

FIG. 9 is another perspective view showing the opened state in FIG. 8;

FIG. 10 is an enlarged view of a portion of the notebook computer in FIG. 1;

FIG. 11 is an enlarged view of a portion of the notebook computer in FIG. 2;

FIG. 12 is an enlarged view of a portion of the notebook computer in FIG. 4;

FIG. 13 is an enlarged view of a portion of the notebook computer in FIG. 5;

FIG. 14 is an enlarged view of a portion of the notebook computer in FIG. 6; and,

FIG. 15 is an enlarged view of a portion of the notebook computer in FIG. 8.

The broken line portions of the notebook computer in FIGS. 1-15 represent unclaimed portions of the claimed design and form no part thereof.

A hinge cap of a notebook computer in a folded state is provided in FIGS. 1-7 and 10-14, and when the notebook computer is transformed to an opened state shown in FIGS. 8, 9, and 15, the hinge cap could be received in a body of the notebook computer, such that the hinge cap is hidden in the view of FIG. 9.

1 Claim, 12 Drawing Sheets
